UNITED STATES PATENT OFFICE.

CHARLES GILBERT HAWLEY, OF CHICAGO, ILLINOIS.

STEAM BOILER.

Application filed June 6, 1923. Serial No. 443,731.

To all whom it may concern:

Be it known that I, CHARLES GILBERT HAWLEY, a citizen of the United States, and a resident of Chicago, Cook County, Illinois, have invented certain new, useful, and Improved Steam Boilers, of which the following is a specification.

The invention relates to steam boilers and their furnaces, with special reference to stationary and marine boilers. My purpose therein is to harmonize the best conditions for the substantially smokeless combustion of "long flaming" fuels with the best conditions for the highly efficient transmission of the heat to the boiler water, including a rapid circulation of the latter; and generally to increase the capacity and efficiency of such boilers, to relatively reduce their size and their cost, to make them safer, simpler to maintain, more durable, and, more quickly and certainly responsive to varying furnace temperatures and rates of combustion.

With these and other objects in view my invention provides a boiler with an underlying combustion chamber or furnace space of a height that permits the flames of such fuel to rise to substantially complete maturity before the gases leave the combustion chamber, thus enabling a most complete and efficient burning of the fuel at any desired rate; and concurrently, my invention insures an efficient and maximum transmission of heat to the boiler water through the medium of a minimum number of boiler heating elements or surfaces and without resort to abnormally high furnace temperatures, this being accomplished by operatively dividing the boiler into two sections which perform substantially distinct duties, the first section directly absorbing the radiant heat of combustion within the combustion chamber and comprising complementary boiler elements which are within said chamber and are of such limited number, form, and arrangement as to greatly subdivide the body of flame and present considerable surfaces thereto and yet avoid premature extinguishment of the flames, while the other section of the boiler is devoted to the absorption of the heat of the combusted and non-flaming gases from the combustion chamber.

In conformity with such conception the heating elements which are located within the combustion chamber are of limited number and small area and yet are fully adequate to the absorption of substantially all of the

radiant heat of the fire. By accepting the greater part of the heat in this state, it becomes possible to secure an increased efficiency and steaming capacity or without loss of efficiency to greatly reduce the total heating area of the boiler as compared with present boilers and the quantity of fuel burned.

As will presently appear the action of the water and steam in the radiant heat absorbing elements causes a definite and rapid circulation of the water throughout the boiler; not alone in the radiant heat absorbing elements but also upon all of those boiler surfaces which are devoted to the absorption of heat by convection; thus raising the efficiency of those surfaces and making it possible to relatively reduce the extent thereof, or to secure a greater quantity of steam therefrom. The active circulation of the boiler water incidentally enhances the durability of the whole boiler and lessens the maintenance cost thereof.

It should now be evident that my invention takes advantage of the fact that in relation to a given heat absorbing surface, radiant heat is many times more available and effective than the heat of non-luminous hot gases; the heat of flaming gases being transmitted in conformity with the laws of light, while actual surface contact is essential to the transfer of heat from merely hot gases.

When such precautions are taken against cooling the burning gases by contact with cold surfaces, the heat radiated by the flaming gases is accepted by adjacent boiler surfaces without materially reducing the temperature of the flame and without interrupting the chemical combination and self-ignition of the continually supplied combustibles. Thus it appears that by my invention the greater part of the heat available in the fuel may be transmitted to the boiler water through radiant heat absorbing elements or water courses of relatively small extent; leaving the conservation of the residual heat of combustion to be performed by the more extensive supplementary surfaces of the boiler. The foregoing statement concerning the virtual non-reduction of flame temperature is not to be confused with the reduction of the flame-body, which of course diminishes toward the top; that is, as the combustion proceeds to maturity.

The gases derived from a substantially

complete combustion, such as here indicated, have a higher temperature than those from a suppressed and incomplete combustion, and volume for volume contain a greater amount of available heat. Only by combustion is the heat liberated, and a suppressed combustion necessarily falls short of liberating all the heat of the fuel. Applying these facts it seems evident that the residual, non-flaming gases from the combustion chamber of a boiler embodying my invention must needs pass to the convected heat section of the boiler at higher temperatures than usual; and, that the thermal efficiency of that section of the boiler is much increased; again making it possible, comparatively, to reduce the total heat absorbing area thereof or conversely to secure more steam therefrom.

The foregoing statements are applicable to long-flaming fuels of all kinds and hence I here call attention to a feature of my invention which has a special relation to ash-containing fuels. It appears that by my invention it becomes possible to fully utilize the heat of many such fuels while working the furnace at temperatures effectively below the fusing or slagging point of the fuel ash. As by this method it is feasible to do so without detriment to the described sustained combustion, I advise as standard procedure the provision of slightly more absorbing surface within the confines of the combustion chamber than actually required for the absorption of all of the radiant heat of the fire. The computation follows well-known rules; the cost of the additional surface is negligible; and, the superabundant surface becomes a substitute for the shortened time element that enters into a higher temperature forced combustion of a fuel, making it possible to avoid a violently hurried combustion that would fuse the ash and result in clinker troubles or in the deposition of slag on the heating surfaces of the boiler. In explanation of these statements it may be noted that the degree of combustion being the same in both cases, as much heat is liberated by a low temperature flame as by one of high temperature, only the more rapid delivery of the heat being in favor of the latter. As there is now no lack of radiant heat absorbing surface closely adjacent the sub-divided flame body in the combustion chamber a hurried combustion is no longer required for the sake of boiler capacity; and where desired it is possible to conduct the active combustion at temperatures which avoid the slagging of the fuel ash and yet make certain of a full recovery of the heat in the described sections of the boiler. Starting with a known furnace temperature directly above the grate or other source of fire, the temperature diminishes as the top of the combustion chamber is closely

approached and the best practice is to design the combustion chamber and the distribution of heat absorbing elements therein so that normally the gases which are extinguished by the exhaustion of combustion and have radiated their quota of heat, shall enter the convected heat section of the boiler at corresponding temperatures, no effort being made to pass into that section either burning gases or such as have temperatures greatly exceeding the ignition temperature of the combustibles in the lower part of the chamber; thus the highest efficiencies are insured. Under these new and favorable conditions it appears that the requirement for excessive furnace temperatures no longer exists and that generally the factor of furnace temperature need be considered only in relation to a desired rate of combustion within a combustion chamber of given size and with respect to the heat resisting and insulating character of the combustion chamber walls.

All of the described heat absorbing elements and surfaces obviously receive heat by convection but for the sake of clearness I have disregarded the convection values of the relatively small radiant heat section of the boiler.

My invention will be still better understood on reference to the accompanying seven sheets of drawings which form parts of this specification. As the invention is capable of embodiment in boilers and settings of both new and old designs or types and as only slight modifications are required to greatly increase the capacity and efficiency of many stationary and marine boilers now in use, I have depicted in the accompanying drawings the number of different embodiments which seems to be required to properly exemplify the invention and the wide scope of its applicability.

Due to their small size the drawings are necessarily somewhat diagrammatic in character but they show all of the elements and essentials of the generic invention as well as many specific forms thereof and will be clearly understood by those who are skilled in the arts of combustion, boiler making, and boiler operation.

Figure 1 of the drawings is a vertical longitudinal section of a steam boiler of the return tube type modified in accordance with my invention; Fig. 2 is a transverse section on the line 2—2 of Fig. 1; Fig. 3 is a like section on the line 3—3; Fig. 4 is a horizontal section substantially on the line 4—4 of Fig. 1; Fig. 5 is a side elevation of a steam boiler of the water tube type embodying my invention, the side wall of the setting being omitted to disclose the complete pressure vessel; Fig. 6 is a sectional detail on the line 6—6 of Fig. 5; Fig. 7 is a special sectional detail illustrating a tube header of a novel form that is specially suited to

the main invention; Fig. 8 is a view like unto Fig. 5, but illustrates still another form of the invention; Fig. 9 is a front elevation thereof partly in section on the line 9—9 of Fig. 8, and partly sectioned on the line 9—9' to show the position of one of the baffles; Fig. 10 is a transverse section of a single storied steam boiler embodying the invention; Fig. 11 is a vertical longitudinal section thereof, better disclosing the header construction; Fig. 12 is a front elevation partly in section on the line 12—12 of Fig. 13, illustrating a modified form of the radiant heat section of a single storied boiler; Fig. 13 is a vertical section on the line 13—13 of Fig. 12, the upper part of the figure being sectioned on the line 13'—13' to disclose the interior of one of the water legs and top drums; Fig. 14 illustrates still another form of my boiler in which the radiant heat section comprises a plurality of stay-bolted water walls; Fig. 15 is a front elevation thereof with one-half in section on the line 15—15 of Fig. 14; Fig. 16 is a vertical section on the line 16—16 of Fig. 17, illustrating a boiler of the type which I term "steeped" and having a radiant heat section of greater heat absorbing capacity than that shown in Figs. 14 and 15; and Fig. 17 is a front elevation taken from Fig. 16 with one-half in vertical section on the line 17—17 of Fig. 16.

To pressure vessels and settings like those shown in Figs. 1 to 9, and Figs. 14 to 17 is given the name "steeped" boilers, as best calculated to identify the same and indicate that the convected heat section is directly superimposed upon the radiant heat section and the combustion chamber which contains the latter. Boilers wherein the convected heat section is merely operatively imposed, being positioned alongside of the combustion chamber and radiant heat section, I term "single-storied" boilers, examples thereof appearing in Figs. 10 to 13.

For the convenience of the reader and a clearer understanding of the usual proportions of my boiler, I have made the accompanying drawings on the scale of one-quarter inch to the foot, (reduced in the printed patent) and generally these proportions may be relied upon; but I wish it to be understood that my invention is by no means limited thereto or to the precise structures illustrated or to the precise proportions or arrangements of parts; for as will become obvious, my invention is capable of embodiment in many forms not here depicted but which fall within the scope of the invention herein described and claimed.

To avoid complication of the drawings I have omitted from most of the drawings all minor parts, such as feed-water connections, steam lines, gages, blow-off connections and many details of the settings, all of which are

well-known to those who are skilled in the art.

For the first exemplary illustration of the invention I have chosen a boiler of the return tube type, being influenced by the fact that such boilers have great need of a method and means for increasing their capacities and efficiencies. I here refer to Figs. 1 to 4 of the drawings, in which I have incorporated a steam pressure vessel or boiler A of the ordinary return tube type occupying a horizontal position on its setting and containing a large number of flues a'. Under my invention this pressure vessel is utilized as the convected heat absorbing section of the boiler. Only a portion of its bottom can be considered as co-acting with the radiant heat section proper.

According to my invention the boiler A instead of being close down over the grate B, is arranged at the top of the tall combustion chamber 1, the walls of which rise at the margins of the grate and constitute the greater part of the setting of the boiler. The ordinary bridge wall becomes a high partition having a throat 2 at the top which leads into the horizontal duct 3, from the rear end of which the gases enter the flues a'. As it is unnecessary to carry the rear part of the setting to the floor I prefer that the duct 3 shall take the trough-like shape, best shown in Fig. 3. Back of the bridge wall is a closure or partition 4 which encloses the chamber 5. The latter accommodates a suitably constructed hollow water wall or header 6, as well shown in Figs. 1 and 3. The boiler water is taken from the bottom of the pressure vessel A by a plurality of down pipes or ducts 7 and it is thereby delivered to the header 6. Extending from the header, through the bridge wall and thence upwardly, are tubes 8, the upper ends of which pass through the bottom of the pressure vessel A. Preferably these tubes 8 are arranged in longitudinally disposed groups so that from the front they present the appearance shown in Figs. 2 and 4, that is, the several groups are separated by wide spaces 9. Practically, these spaces are wide enough to admit a man who may be called upon to work upon them or to replace the tubes.

Such width gives ample assurance that the presence of the water containing tubes will not materially suppress the flames from the bed of the fire on the grate. Thus it comes about that the flames from the grate, or other origin of the fire, have a free and uninterrupted rise in the tall spaces between the groups of tubes 8. In practice the combustion chamber 4 is from eight to twelve feet in height and with some fuels the firing space may be as much as twenty feet in height. From this it will be apparent that fuels of all sorts may be accommodated, the essential feature being that the flames from

the fuel shall be allowed to rise without suppressive resistance to the point of substantially complete flame propagation and maturity, so that little if any flame shall pass into the convected heat section of the boiler. Such are the conditions for the very best combustion and the highest efficiencies and obviously these dimensions being responsive to known rules of kind and rate of combustion are within the determination of the skilled artisan. Figures 1 and 2 quite clearly show the subdivided flame action in the combustion chamber and those who are familiar with the art will at once comprehend the fact that the flames give off their heat by radiation to the relatively extensive surface afforded by the many tubes 8. In practice each square foot of radiant heat absorbing surface (tubes 8 in this case) thus submerged in the body of flame may be depended upon for an evaporation of from 30 to 60 pounds of water per square foot per hour and where special firing arrangements are made a greater evaporation may be obtained. It should be apparent that while the heat absorbing area of the radiant heat tubes 8 is almost minute in comparison with the area afforded by the flues α' , their evaporating efficiency is so much greater per square foot as to effectively provide an absorbing surface fully equal to and under the best practice somewhat exceeding the heat radiating capacity of the quantity of fuel burned. Of such simple and relatively small elements is the radiant heat section composed. The rapid generation of steam in the tubes 8 results in continuously displacing much of the water therein, making the column of water in each tube 8 much lighter than the columns in the descending or return tubes 7. Consequently an extremely rapid circulation of all of the boiler water is set up within and through the radiant heat section of my boiler, insuring the best evaporative conditions in the radiant heat section, and virtual freedom from scale formation, and a like circulatory action throughout the pressure vessel A, with like advantages in the matter of steam liberation and freedom from scale deposits. 10 represents the steam outlet of the boiler. A blow-off connection (not shown) is usually provided at the rear end of the pressure vessel A and at the bottom of the cross header 6. I have attempted to represent both the water and the steam in the body of the boiler. The short arrows in Figs. 1, 2 and 3 represent the action of the boiler water. The feathered arrows indicate the course of the non-luminous or residual gases which on leaving the combustion chamber, pass through the flues of the pressure vessel and finally, at a proper low temperature, escape through the breeching 11. It will be found that even where the combustion chamber height, or free flame rise, hav-

ing been fixed in the construction of the boiler is afterward found to be too low under conditions of forced firing, the preponderating effect of the flame-submerged radiant heat section is amply sufficient to afford a very great increase in the steaming capacity of the boiler and a marked betterment of efficiency. In constructing the boiler and setting it is, however, better to err on the side of an excessive height in the combustion chamber in order that substantially all of the very effective radiant heat of combustion shall certainly be used and shall be made to benefit all other heating surfaces of the boiler by promoting the described rapid circulation of the whole body of boiler water.

In Figs. 5 to 9 I have shown the application of my invention to water tube boilers of well-known types. Thus in Fig. 5 I have shown the familiar pressure vessel comprising a top drum 12 and headers 13 and 14 and the inclined banks of tubes 15, to which I have added the header extension 14', the radiant heat absorbing groups of tubes 16, the back header 17, and the return tubes or ducts 18, 18' and 18''. In side elevation each flame-submerged group or wall of tubes 16 presents a very extensive heat absorbing surfaces. In end elevation the tubes partake of the appearance in Fig. 6, where it will be seen that the several groups are separated by the before described wide flame propagation spaces 19. These tubes are arranged in the tall combustion chamber 20, the flames passing upward between the groups or tubular partitions, as indicated by the short full-line arrows. The longer full-line arrows represent the sweep of the combusted and non-luminous gases, as directed by the usual baffles 21 and 22. The dotted arrows represent the circulatory movement of the water, and in the upper forward parts of the pressure vessel the dotted arrows represent the movement of the mixed steam and water. Obviously I have herein presented a boiler comprising the hereinbefore described two sections; one devoted to the absorption of the radiant heat, and the other to the absorption of heat by convection, together with a combustion chamber wherein a maximum of radiant heat may be developed under proper conditions.

Figures 8 and 9 show how a boiler embodying my invention may be made up of sectional headers and water tubes. The convected heat section of the boiler is a reproduction of one of the many boilers now in use. The radiant heat section is made up of a plurality of individual sectional headers 23 and their tubes 24. In this simple manner I provide the vertically disposed tubular partitions separated by vertical flame propagation spaces 25, as required by my invention. The parts 26 and 27 are cross headers having an obvious function, and to which I

prefer to attach blow-off pipes, for the certain removal of accumulations of solids. In practice, the height from the grate to the bottom of the convected heat section is sufficient to allow the fuel flames to rise to substantial maturity before passing into the group of heat convection tubes.

The delivery of steam from the radiant heat absorbing tubular partitions is extremely rapid due to the high efficiency of the heat transmission from flame to water; and to avoid congestion in the riser headers, either individual or group headers may be provided in accordance with Fig. 7. I have therein shown a header 28 having one steam and water course 29 for the convected heat section 30 of the boiler and a separate water course 31 for the radiant heat section 32 of the boiler. These sections are not closed off from communication as there are numerous openings in the mid partition 33; therefore the balance of pressures is properly preserved throughout the header. A header involving this principle is extremely desirable; a fact which will be appreciated when it is understood that the radiant heat absorbing section of any of my boilers may be depended upon to generate a very much greater volume of steam than comes from the much larger heating surfaces offered by the convected heat section of the boiler. The statement as to the comparative capacities of the radiant and convected heat sections will be found to be true for all furnace operations with long-flaming fuels and with furnace temperatures as low as 1800 degrees F.

Wishing it to be understood that my invention is by no means limited to the "steeppling" of the radiant and convected heat sections of the boiler, I have illustrated single-story forms thereof in Figs. 10 to 13. Little change is required. The combustion chamber 34 with its vertical tubular partitions 35, and tall upright flame spaces 36, is arranged side by side with the convected heat absorbing sections 37 and 38; all within a single setting. It is, of course, understood that the radiant heat section of the boiler comprises relatively few water tubes while the convected heat section is made up of a great number thereof placed close together as required for the more difficult absorption of heat from the non-luminous gases received from the top of the combustion chamber. Obviously in this and in the other forms of my boiler the tubes of the convected heat section may be arranged one above the other or may be staggered according to the wish of the designer. In Figs. 10 and 11 the front and back of the boiler comprise headers 39, of any suitable construction; the side walls are usually made of brick, likewise the intermediate walls or baffles. The roof of the boiler is composed of the usual steam collecting drums 40 together with their connecting

tubes and suitable bricks supported by the latter. The steam outlet 41 is preferably arranged over the convected heat section of the boiler where the agitation of the boiler water is least active.

70

At the cost of a considerable increase in weight, but with individual advantages the radiant heat section of my boiler may be made of hollow stay-bolted water walls such as the walls 42 shown in Figs. 12 and 13. 75 For each of these walls I preferably provide a top steam drum 43. All of these drums are best connected by cross headers 44 which join the headers 45 of the convected heat absorbing section 46. At the bottoms the 80 water walls 42 are provided with bulging tube-like portions 47. At the end of each portion 47 is an intake neck 48 while at the other end is a blow-off connection 49. The intake connections of the several walls are 85 connected with a cross header 50, and this is supplied with return water through the agency of a large number of down tubes 51 leading from the overlying cross header 44. It is unnecessary to detail the operation and 90 action of the boiler as by now both will be clearly understood from prior descriptions herein. The dead or exhausted gases leave the tops of the flame spaces 52 through the end openings 53. These increases in size 95 toward the intercommunicating throat 54, as well indicated by the dotted lines 55 in Fig. 15. Except for some such construction the relief of the exhausted gases would be 100 impeded. The structural details will be clearly understood from Figs. 12 and 13. The construction of the convected heat section 46 is substantially the same as indicated in Figs. 10 and 11; the same comprising 105 front and back headers and a large number of closely spaced water tubes. The steam outlet is associated with that part of the boiler.

That my invention is not limited to a particular mechanical construction or to the 110 employment of straight tubes and headers is clearly suggested by the structure which I have shown in Figs. 14 and 15. The same comprises a steeped radiant heat boiler composed of the now familiar radiant heat section and the superimposed convected heat section. In this case the radiant heat section comprises a plurality of spaced apart water walls 56 each having a top drum 57, plus return tubes 58, and return headers 115 or drums 59 which connect with respective intakes 56'. But in this case the drums 57 are spaced apart to provide the gas passages 60 which lead upward into the convected heat section. The convected heat section 120 comprises a large number of banks or courses of bent water tubes 61, which connect the drums 57 with the steam collecting drums 62. By preference all of the headers 59 are joined together as by connections 59'. Like- 125

wise by preference all of the steam drums 62 are joined by a cross steam drum or collector 63. Thus the proper balance is insured and maintained throughout the boiler. The structure has many practical advantages, among which may be mentioned the fact that in effect the boiler here shown is composed of four boiler units, each of said units comprising a drum 62, tubes 61, a drum 57, a water wall 56, a header 59, and return tubes 58. By this construction it becomes possible to easily provide and to easily erect boilers of many sizes and capacities, but all composed of units which are identical. As herein indicated, it is a simple matter to incorporate in any of my boilers a superheater; utilizing convenient spaces for the accommodation of the heating elements thereof. In Figs. 14 and 15 such heating elements of the superheater are marked 64, all of which join the steam headers 65 and 65'. Other mechanical details of the structure will be readily understood on close examination of the drawings.

For the double purpose of elaborating the above described unitary or sectional idea, as applied to steam boilers, and to make it clear that the conception of the sectional boiler is not restricted to the use of stay-bolted water walls of the kind hereinbefore described, I have shown in Figs. 16 and 17 a novel boiler which is made up of units or sections of another form and incorporating radiant heat absorbing partitions which comprise a large number of water tubes. The tubes just referred to are marked 66. They are supplied by down headers 67; that is, headers in which the boiler water moves downward, thence passing upward through the tubes 66 in the presence of the hot flames from the lower part of the combustion chamber 68. The mid-drums 69 here shown resemble the drums 57 of Figs. 14 and 15. Likewise the top drums 70 resemble the drums 62 before described. But in place of a single radiant heat absorbing partition, units of the kind shown in Figs. 16 and 17, accommodate two or more such partitions, that is, each drum 69 and each pair of down headers 67 accommodate two of the vertically disposed groups of tubes 66. They are so disposed that like the radiant heat groups or partitions before described, they do not obstruct or materially interfere with the free continuity and propagation of the flames. The convected heat section of each unit is completed by a large number of water tubes 71 so placed as to be readily accessible in case a tube needs to be removed. It is obvious that there is ample space for access to all the tubes in the radiant heat section of the boiler.

A peculiar advantage of the structure under discussion lies in the fact that the comparatively narrow water walls or down

headers 67 are placed edge to edge and form the front and back walls of the combustion chamber, adding their inner surfaces to the radiant heat absorbing section of the boiler. The structure including the boiler setting is sufficiently detailed for the understanding of anyone who is skilled in the art. But it may be pointed out that the pressure vessel is supported from the tops of the parts 67 as by the cross beams 72. And individual tubes 67' are preferably employed between the tops of the hollow section 67, and respective drums 70.

It will be observed that my novel steepled boilers have the advantages attaching to great capacity, high efficiency, and the occupancy of a small floor space, to which is added the common advantage of all of my boilers, i. e., the heating surfaces are uniformly more efficient than those of ordinary boilers. These pressure vessels may be smaller and of lower cost than those of equal capacity, which are in present day use. I have not attempted to illustrate means for the burning of oils and gases under these boilers as I regard the illustration of coal-burning furnaces as fundamental and inclusive of furnaces of all kinds. Except that in some instances the proportions of the boilers may be advantageously modified or fixed in advance with reference to a certain fuel or fuels, it is true that all of my boilers may be and are adapted to be fired with fuels of any and all of the long-flaming kinds. In comparison with other boilers my invention greatly multiplies the extent of heat absorbing surface which is exposed to the radiant heat of the fire. This long sought result and the many benefits flowing therefrom are all attained in structures which in addition thereto have the advantage of durability, easy maintenance, comparatively low costs and the occupancy of less fire room space.

Having thus described my invention, I claim as new and desire to secure by Letters Patent:—

1. A casing or setting containing a tall combustion chamber admitting of the substantial maturity of an upright body of long-flaming fire, in combination with a steam boiler, the major extent of which is positioned to receive the hot gases from said chamber, and, having heat absorbing portions of minor extent that vertically partition said chamber, divide the flame body therein substantially throughout the height of the chamber and permit the flames to rise to the top thereof, thus allowing the development of a maximum of heat from the fuel burned, increasing the radiant area of the flame body and the absorption of radiant heat therefrom and correspondingly reducing the heat absorbing duty of said major extent of the boiler.

2. A casing or setting containing a tall

combustion chamber admitting of the substantial maturity of an upright body of long-flaming fire, in combination with a steam boiler, the major extent of which is positioned to receive the hot gases from said chamber, and, having heat absorbing portions of minor extent that partition said chamber into a plurality of vertical passages, subdivide the flame body therein substantially throughout the height of said chamber and permit the flames to rise to the top thereof, thus allowing the development of a maximum of heat from the fuel burned, increasing the radiant area of the flame body and the absorption of radiant heat therefrom and correspondingly reducing the heat absorbing duty of said major extent of the boiler.

3. A casing or setting containing a tall combustion chamber admitting of the substantial maturity of an upright body of long-flaming fire, in combination with a steam boiler composed of two sections, the first comprising a major extent of heat absorbing surfaces positioned to receive the hot gases from said chamber, and, the second being in circulatory union with the first and comprising heat absorbing portions of minor extent that vertically partition said chamber into a plurality of upright passages, divide the flame body therein substantially throughout the height of said chamber and permit the flames to rise to the top thereof, thus allowing the development of a maximum of heat from the fuel burned, increasing the radiant area of the flame body and the absorption of radiant heat therefrom and correspondingly reducing the heat absorbing duty of said major extent of the boiler.

4. A casing or setting containing a tall combustion chamber admitting of the substantial maturity of an upright body of long-flaming fire, in combination with a steam boiler, the major extent of which is positioned above said chamber to receive the hot gases from the top thereof, and, having heat absorbing portions of minor extent that vertically partition said chamber, divide the flame body therein substantially throughout the height of the chamber and permit the flames to rise to the top thereof, thus allowing the development of a maximum of heat from the fuel burned, increasing the radiant area of the flame body and the absorption of radiant heat therefrom and correspondingly reducing the heat absorbing duty of said major extent of the boiler, all within a minimum of floor space.

5. A casing or setting containing a tall combustion chamber admitting of the substantial maturity of an upright body of long-flaming fire, in combination with a steam boiler composed of a plurality of vertical sections placed side by side and each

comprising a major extent of heating elements positioned above said chamber and devoted to the absorption of the heat of the gases from said chamber, and, underlying heat absorbing portions of minor extent that vertically partition said chamber, divide the flame body therein substantially throughout the height of the chamber and permit the flames to rise to the top thereof; allowing the development of a maximum of heat from the fuel burned, increasing the radiant area of the flame body and the absorption of radiant heat therefrom and correspondingly reducing the heat absorbing duty of the major or upper portion of the boiler.

6. A casing or setting containing a tall combustion chamber admitting of the substantial maturity of an upright body of long-flaming fire, in combination with a steam boiler composed of a plurality of vertical sections placed side by side and each comprising a major extent of heating elements positioned above said chamber and devoted to the absorption of the heat of the gases from said chamber, and, underlying heat absorbing portions of minor extent that vertically partition said chamber into a plurality of upright passages, divide the flame body therein substantially throughout the height of the chamber and permit the flames to rise to the top thereof; allowing the development of a maximum of heat from the fuel burned, increasing the radiant area of the flame body and the absorption of radiant heat therefrom and correspondingly reducing the heat absorbing duty of the major or upper portions of the boiler.

7. A casing or setting containing a tall combustion chamber admitting of the substantial maturity of an upright body of long-flaming fire, in combination with a steam boiler, the major extent of which is positioned to receive the hot gases from said chamber, and, having vertical groups of water circulating and heat absorbing tubes of minor extent that partition said chamber into a plurality of vertical passages, subdivide the flame body therein substantially throughout the height of said chamber and permit the flames to rise to the top thereof; the same allowing the development of a maximum of heat from the fuel burned, increasing the radiant area of the flame body and the absorption of radiant heat therefrom and correspondingly reducing the heat absorbing duty of said major extent of the boiler.

8. A casing or setting containing a tall combustion chamber admitting of the substantial maturity of an upright body of long-flaming fire, in combination with a steam boiler, the major extent of which is positioned to receive the hot gases from said chamber, and, having vertical groups of

spaced heat absorbing, circulating tubes of minor extent that partition said chamber into a plurality of vertical passages, subdivide the flame body therein substantially throughout the height of said chamber and permit the flames to rise to the top thereof; the same allowing the development of a maximum of heat from the fuel burned, increasing the radiant area of the flame body and the absorption of radiant heat therefrom and correspondingly reducing the heat absorbing duty of said major extent of the boiler.

9. A casing or setting containing a tall combustion chamber admitting of the substantial maturity of an upright body of long-flaming fire, in combination with a steam boiler, the major extent of which is positioned above said chamber to receive the hot gases from the top thereof, and, having vertical groups of spaced heat absorbing tubes of minor extent that vertically partition said chamber, divide the flame body therein substantially throughout the height of the chamber and permit the flames to rise to the top thereof; the same allowing the development of a maximum of heat from the fuel burned, increasing the radiant area of the flame body and the absorption of radiant heat therefrom and correspondingly reducing the heat absorbing duty of said major extent of the boiler.

10. A casing or setting containing a tall combustion chamber admitting of the substantial maturity of an upright body of long-flaming fire, in combination with a steam boiler composed of a plurality of vertical sections placed side by side and each comprising a major extent of heating elements positioned above said chamber and devoted to the absorption of the heat of the gases from said chamber, and, underlying radiant heat absorbing portions of minor extent chiefly composed of groups of spaced water circulating tubes that vertically partition said chamber into a plurality of upright passages, divide the flame body therein substantially throughout the height of the chamber and permit the flames to rise to the top thereof, the same allowing the development of a maximum of heat from the fuel burned, increasing the radiant area of the flame body and the absorption of radiant heat therefrom and correspondingly reducing the heat absorbing duty of the major or upper portions of the boiler, all within a minimum of floor space.

10. A casing or setting containing a tall combustion chamber admitting of the substantial maturity of an upright body of long-flaming fire, in combination with a steam boiler composed of a plurality of vertical sections placed side by side and each comprising a major extent of heating elements positioned above said chamber and devoted to the absorption of the heat of the gases from said chamber, and, underlying radiant heat absorbing portions of minor extent chiefly composed of groups of spaced water circulating tubes that vertically partition said chamber into a plurality of upright passages, divide the flame body therein substantially throughout the height of the chamber and permit the flames to rise to the top thereof, the same allowing the development of a maximum of heat from the fuel burned, increasing the radiant area of the flame body and the absorption of radiant heat therefrom and correspondingly reducing the heat absorbing duty of the major or upper portions of the boiler, all within a minimum of floor space.
